UNITED STATES PATENT OFFICE

172,829

DOLL

Elvira A. Fish, Elgin, Ill.

Application December 16, 1953, Serial No. 28,086

Term of patent 7 years

(Cl. D34—4)

To all whom it may concern:

Be it known that I, Elvira A. Fish, a citizen of the United States, residing at Elgin, county of Kane, State of Illinois, have invented a new, original, and ornamental Design for a Doll, of which the following is a specification, reference being had to the accompanying drawing, forming a part hereof.

Fig. 1 is a front view of a doll showing my new design.

Fig. 2 is a side view taken from the right of Fig. 1; and

Fig. 3 is a rear view of the doll.

I claim:

The ornamental design for a doll, substantially as shown.
